DESIGN FOR A CASING FOR AUTOGRAPHIC
REGISTERS

Walter D. Teague, New York, N. Y., assignor, by
mesne assignments, to American Sales Book
Company, Inc., a corporation of Delaware

Application December 7, 1934, Serial No. 54,332

Term of patent 14 years

To all whom it may concern:

Be it known that I, Walter D. Teague, a citizen of the United States, residing at New York, in the county of New York and State of New York, have invented a new, original, and ornamental Design for Casings for Autographic Registers, of which the following is a specification, reference being had to the accompanying drawing, forming part thereof.

Fig. 1 is a perspective view of a casing for an autographic register showing my new design as it appears when looking toward one corner of the casing;

Fig. 2 is a perspective view of the same as seen when looking toward the diagonally opposite cor-

ner of the casing from that as viewed in Fig. 1; Fig. 3 is an end elevation of the casing; and

Fig. 4 is an end elevation of the opposite end of the casing from that shown in Fig. 3.

The cross-hatching indicates a solid color, preferably black. Otherwise the outside of the casing is light colored in contrast to the black.

I claim:

The ornamental design for a casing for autographic registers, as shown and described.

Signed at New York, in the county of New York and State of New York, this 26th day of November, 1934.

WALTER D. TEAGUE.
